UNITED STATES PATENT OFFICE

94,780

DESIGN FOR A LAMP

Ruby McRae Strahmann, New York, N. Y.

Application January 7, 1935, Serial No. 54,763

Term of patent 3½ years

To all whom it may concern:

Be it known that I, Ruby McRae Strahmann, a citizen of the United States, residing at New York, in the county and State of New York, have invented a new, original, and ornamental Design for a Lamp, of which the following is a specification, reference being had to the accompanying drawing, forming part thereof.

The figure is a perspective view of a lamp. The petals surrounding the bulb comprise tinted and colored shells, as do the leaves on the stems surrounding that supporting the lamp. The various stems are colored green and made of material

resembling natural plant growth. The ornamental figure on the flower pot is also colored. The flower pot and the base are also colored. The granular substance from which the plant protrudes is colored to resemble sand, earth, or the like.

I claim:

The ornamental design for a lamp substantially as shown and described.

In testimony whereof, I affix my signature.

RUBY McRAE STRAHMANN.
